CURTAIN ROD BRACKET

Alfons Glassenhart, 2425 E. Sheridan, and William J. Stoltz, 4601 E. Oak, both of Phoenix, Ariz.

Filed May 31, 1960, Ser. No. 60,779

Term of patent 14 years

(Cl. D21—1)

Fig. 4

Fig. 2

Fig. 1

Fig. 3

Fig. 5

Fig. 1 is a front elevational view of a curtain rod bracket embodying our new design;

Fig. 2 is a left side elevational view thereof;

Fig. 3 is a right side elevational view thereof;

Fig. 4 is a top plan view; and

Fig. 5 is a bottom plan view thereof.

The broken line partial showing of a curtain rod is for illustrative purposes only.

We claim:

The ornamental design for a curtain rod bracket, as shown and described.
